REVERSIBLE DOOR LATCH

Albert F. Lickteig, Jr., Grand Rapids, Mich.

Application September 9, 1948, Serial No. 48,455

1 Claim. (Cl. 292—244)

1. 2

This invention provides an improvement in door latch construction whereby conventional latch mechanisms may be adapted for the factory installation of the latch within the door. Such factory installation has heretofore been impractical due to the necessity of manufacturing for stock a large number of doors which are adapted to swing in one direction only. Conventional latches are adapted to lock from one direction only, and when once installed in a door require almost complete removal therefrom and reinstallation in order to lock from the opposite direction. The present invention makes possible the changing of the direction of locking by merely removing the front plate from the latch mechanism and effecting a minor adjustment to the bolt, leaving the balance of the latch mechanism as originally installed. It is obvious that there is considerable advantage to be obtained from installing door latches at the factory, since in this manner it is possible to obtain the savings which follow from mass production techniques. These advantages are especially important in view of the fact that the structural modifications which are necessary to adapt conventional latches to the use of this invention are relatively minor, and generally do not require extensive modification of the usual retracting mechanism and case.

The features which are outlined above are obtained by providing a support for the latch bolt which positions it substantially on the axis of retraction, while leaving the bolt free to rotate about that axis. In addition to this axial support, the angular position of the bolt about such axis is left to be determined by the manner in which the bolt engages the conventional front plate well known in latch construction. This front plate is conventionally provided with a bolt-receiving aperture, the usual practice being to form both bolt and aperture in a square or rectangular cross section. It is clear that once the bolt engages the aperture (with usually a relatively close fit) that the angular position of the bolt about its axis would be definitely determined. With this type of arrangement, the removal of the front plate from the assembled latch mechanism leaves the bolt free to be rotated so that a locking surface of the bolt may be presented to either one face or the other of the door, thus allowing the door to be hung in any location. Such a latch mechanism may be completely installed in the door (including knobs and related structure, if desired), and the position of the latch bolt changed after the door is hung in position, if such bolt did not happen to be facing

in the direction required by the particular installation.

The latch mechanism may also be installed in the factory without the front plate in position, 5 and the plate installed by the carpenter on the job. In this latter case, it is highly desirable that means be provided to prevent the ingress of foreign material, chips, etc., in and about the aperture occupied by the latch mechanism in 10 the door. The present invention accordingly provides closure means for substantially preventing such ingress while preserving the rotatability of the bolt about its axis and in no way interfering with the action of the supporting structure. In 15 the preferred form contemplated by this invention, the supporting means for the bolt and closure means are combined.

The feature of providing sliding support for the bolt which is independent of the front plate is 20 valuable for several reasons. Without such provision, the bolt is left in a somewhat indeterminate position as soon as the front plate is removed. This of course renders the reinsertion of the front plate somewhat troublesome, since 25 it is necessary first to locate the bolt within the aperture and then attach the front plate in position. It is also obvious that unless the bolt is well supported when the front plate has been removed, the latch mechanism is highly vulnerable 30 to injury which might be caused by objects striking the bolt, particularly from a lateral direction. This situation would render it extremely risky to attempt to install a latch mechanism in the factory and ship the same with the front plate removed, as is often done in installations requiring a front plate having a particular finish.

The rotatable support of the bolt as outlined 35 above is accomplished preferably by providing the bolt with a washer-shaped bearing member which is closely associated with the bolt structure. The passageway which is adapted to guide the bolt to a retractive position is formed to accommodate the outer shape of this bearing member. With 40 this arrangement, the position of the bolt within the passageway is generally determined by the bearing member. If the passageway is other than circular in cross section, the outer periphery of the bearing member may be either circular and of such diameter as to be tangent to the sides 45 of the passageway, or may be of square or other such rectangular cross section as to fit within the passageway. In the latter case a circular central aperture would be provided to receive a link connecting the bolt with the retracting mechanism.

An alternative system for supporting the bolt for rotation about its axis comprises a circular passageway of such a diameter as to receive the usual bolt which is square in cross section, contact being effected at the four corners of the bolt. With this arrangement, the bolt is free to rotate about its axis as soon as the front plate is removed, its angular position being determined as soon as the bolt engages the aperture in the front plate and the said front plate is firmly attached in position. With this arrangement, as well as that indicated in the preceding paragraph, the supporting structure of the passageway tends to reinforce if not entirely supplant the supporting action of the front plate, so that the strain thereon is considerably relieved. With this construction, it is well within the range of possibility to provide a front plate which normally has no part in furnishing the force which permits the bolt to lock the door, enough clearance in the aperture being provided so that the forces generated by the passageway and associated structure are sufficient for this purpose. The only function of the front plate or its equivalent in such an installation is to determine the angular position of the bolt about its axis.

The various features of this invention will be described in detail by an analysis of particular devices and components which are illustrated in the accompanying drawings. In these drawings:

Figure 1 illustrates a plan view section through a latch mechanism embodying the present invention.

Figure 2 illustrates a section along the plane 2—2 indicated in Figure 1.

Figure 3 illustrates a modified form of this invention to that shown in Figure 1.

Figure 4 illustrates a section on the plane 4—4 of Figure 3.

Referring to Figures 1 and 2, the latch mechanism 19 is shown installed in the bore 11 within the door 12. The knob or other actuating mechanism for the latch is not shown, but provision is made for the installation thereof by providing the hole 13 which intersects the bore 11. A suitable actuating bar which is associated with the knob or other handle is installed within the hole 13 to cooperate with the retracting mechanism generally indicated at 14. A retracting mechanism generally similar to that shown in Figure 1 is described in detail in the application of Albert F. Lickteig, Jr., Serial Number 30,755, and filed on June 3, 1948. Since the details of the retracting mechanism form no part of the present invention, this portion of the drawing will not be considered at length.

The bolt 15 is provided with the locking surface 16 and the slanted surface 17. As the door is closed, the striker plate located on the door jamb contacts the slanted surface 17 which then acts as a ramp and causes the bolt to be forced inwardly to a retracted position to permit the door to close. When the locking aperture of the striker plate and the bolt are in alignment, the bolt then returns to the position shown under the urging of spring 18.

The connection of the bolt to the retracting mechanism 14 is effected by the link 19 which is firmly fixed to the bolt at its outer end, the inner end being slidably retained by a suitable aperture in the face of the crosshead 20. The inner end of the link 19 is equipped with an enlarged portion 21 which prevents the link 19 from being withdrawn from the crosshead. In this particular mechanism, the enlarged portion 75

21 acts as a stop which limits the outward movement of the bolt under the urging of spring 18.

The latch mechanism illustrated in Figures 1 and 2 is provided with a case 22 which is substantially rectangular in cross section. The bearing member 23 is slidably retained within the case 22, and is provided with a central aperture 24 which receives the link 19. The engagement of the sides of the aperture 24 and the link 19 is such that rotation of one member with respect to the other is permitted. In this manner it is possible for the bearing member to slide within the confines of the case 22 and support the bolt in the central portion thereof without interfering with the rotation of the bolt about its axis which may be generally indicated at 25. In a similar manner, the aperture in the crosshead 20 is preferably adapted to slidably retain the link 19 while permitting the same to rotate. It is of course possible to provide a rotatable mounting of the bolt 15 upon the link 19 and thus do away with the rotatable engagement of the aperture 24 and the crosshead 20 with the link 19. In this latter case, it would only be necessary to provide for sliding engagement in the crosshead 20 and a fixed attachment of the bearing member 23 to the link 19. Generally speaking, however, it is more practical to form the structure as indicated, due to the complexities and problems involved in rotatably supporting the bolt upon the link.

The front plate 26 is provided with the aperture 27 which engages the bolt 15 in such a manner that sliding of the bolt is permitted. The shape of the bolt and of the aperture are such that relative rotation of one to the other is not possible when once the bolt has been inserted therein. The position of the front plate 26 with respect to the balance of the latch mechanism is secured by the locating recess formed by the flanges 28 which are rigidly connected to the balance of the latch structure by means of the rivets 29.

Referring to Figures 3 and 4, a modified form of this invention is illustrated in which the bolt is supported without the use of a bearing member similar to that indicated at 23 in Figures 1 and 2. The case 30 is circular in cross section as best indicated in Figure 4, and of such diameter as to permit the passage of the bolt 31. The bolt is thus permitted to slide on its corners as it moves to and from a retracted position. The front plate 32 is provided with the aperture 33 which engages the bolt 31 in the same manner as is shown in Figure 1. The front plate 32 is securely supported with respect to the balance of the latch mechanism by means of the same construction as is indicated in Figure 1, namely the flanges 34 which are securely fastened to the case by means of the rivets 35.

The proportions of the aperture 33, if desired, may be such that the entire supporting force which maintains the bolt 31 in position against locking action may be contributed by the case 30, or the aperture may fit the bolt closely so as to bear against the same and provide the major part of the locking action. In the latter case, the removal of the front plate 32 leaves the bolt to be supported by the action of the case 30 bearing against the corners of the bolt. It is preferable that the supporting action of the case 30 as indicated be such that the bolt be maintained close to the position that it would have when the front plate is attached, thereby minimizing the amount of adjustment necessary to fit the bolt

within the front plate before fastening the same to the balance of the structure.

The entire assembly which has been discussed above is secured in position in the door by means of wood screws, according to conventional practice, which serve to secure the front plate within the flanges 28 or 34, and to fasten the entire latch mechanism in its proper location within the door.

An added effect of the bearing member 23 in Figure 1 is the establishment of a closure to the bolt passageway when the front plate 26 is removed from position. The presence of this closure forms a barrier to the ingress of shavings, foreign material, and the like which might interfere with the operation of the latch mechanism. This feature permits the insertion of the latch within the door at the factory, and shipping the same without the front plate in position. This practice has an advantage when it is desired to provide a door with a special surface and a special front plate to match therewith. The closure effect can also be provided in the mechanism shown in Figure 3 by the simple addition of the washer 36 which has an inner aperture adapted to receive the link 37, and an outer diameter adapted to be slidably retained by the walls of the case 30. Both bearing member 23 and washer 36 are preferably maintained in position by the action of the springs which bias the bolt in an outward direction. If desired, these members may be provided with elongated bearing portions to increase their stability.

The particular mechanisms which are illustrated in the accompanying drawings and described herein are for illustrative purposes only. The definition of this invention and the scope

thereof are to be obtained from the claim which is appended hereto.

I claim:

5 A latch mechanism comprising a casing having a tubular wall defining a passage, a bolt having a head retractable into said passage and a shank, said head having a latching surface and an opposed inclined surface, retracting means carried by said casing rotatably interconnected with said head whereby said head can be turned about its longitudinal axis, a bearing member located in said tubular member adjacent said head and containing a perforation receiving and substantially complementing said shank, said bearing member having a periphery substantially complementing and slidably engaging said tubular wall, and a plate detachably and replaceably secured to said casing having an opening substantially complementing a portion of said head and restraining said bolt against rotation, said bearing member substantially closing said passage against the introduction of foreign matter when said plate is detached.
